ELECTROACOUSTIC DEVICE

James Samuel Paterson Roberton, London, England, assignor to International Standard Electric Corporation, New York, N. Y.

Application May 12, 1942, Serial No. 442,655
In Great Britain November 29, 1940

3 Claims. (Cl. 179—114)

This invention relates to telephone receivers and transmitters, and is applicable to transmitters and receivers for batteryless or "sound-powered" telephones, as well as to ordinary telephone receivers used on handsets and headsets and as watch receivers. The units could be made in capsule form or as insets in which the parts are clamped together by the earcap.

Among the features of the invention is the use of a balanced armature principle, in which the armature is a magnetic diaphragm. This has the normal advantages of a balanced armature system, viz. high efficiency due to polarising flux not passing through the armature, and no distortion due to harmonics.

In addition it has further advantages due to the construction adopted, viz., a light moving system owing to combination of armature and diaphragm (the magnetic armature can be made very thin because it does not carry polarising flux), the magnet faces are ground in the same plane and the working gaps can be made very small and accurate by using spacing washers of controlled thickness, and a sealed-in capsule construction can readily be applied to the design, with the advantage of keeping magnetic particles and dirt from the small airgaps of the balanced armature system.

In order that the invention may be clearly understood, a description will be given of certain of its embodiments, reference being made for this purpose to the accompanying drawings.

In those drawings:

Figs. 1 and 2 are central sections at right-angles to one another through a first embodiment;

Figs. 3 and 4 are similar sections through a second embodiment;

Figs. 5 and 6 are similar sections through a third; and

Fig. 7 is a central section through a modification of the first embodiment.

Referring to Figs. 1 and 2, each of the magnets 11 and 12 is annular in shape with a channel section, having an inner ring forming one pole and an outer ring forming the other pole of the magnet. The polar faces are preferably ground in the same plane. The two magnets 11 and 12 are magnetised with opposite polarity and are arranged face to face clamping between them a magnetic (i. e. magnetisable) diaphragm 13 spaced by magnetic washers 14 and 15. The inner poles of the two magnets are thus arranged in juxtaposition on opposite sides of the diaphragm; and as they are of opposite polarity the

lines of magnetic flux will pass straight through the diaphragm, traversing it in a direction substantially normal to its plane. Windings 16 and 17 are assembled in the annular recesses of the magnets and sealed in with a suitable sealing compound. The windings are connected together at 18 and insulated leads 19 and 20 connect respectively to terminal 21 and case 22. The connection and sense of the two windings is such that at any instant when current is flowing through them the radial magnetic fluxes produced in the diaphragm 13 are additive, in other words the current at any instant will create poles of like polarity in juxtaposition on opposite sides of the diaphragm. Thus, considering both the steady flux and the flux due to speech (the term speech being of course a quite general one and not limiting the use of the instrument to the conveyance of human articulation), it may be said that, substantially if not wholly, the fluxes traverse the diaphragm in directions which are, for the steady flux, normal to its plane and for the flux due to speech parallel to its plane. It will be clear that according to the direction of the current and hence of the radial fluxes produced, the diaphragm will be deflected towards either magnet 11 or magnet 12.

The magnets, coils and diaphragm are assembled inside a casing 23 preferably of moulded insulating material. The terminal 21 is of circular shape with a projecting tag and is located centrally in a recess in the casing 23. The tag is formed at right angles and enters a longitudinal groove in the cylindrical wall of casing 23. A central hole in terminal 21 is covered with acoustic resistance material 24 such as silk, and is a continuation of a similar hole in case 23. An insulating washer 25 is of such a size that it just overlaps terminal 21 and serves to insulate it from the outer metal case 22. The latter is preferably of thin sheet non-magnetic metal, and has an aperture rather larger than that in the washer 25. The flat end surfaces of terminal 21 and case 22 then serve as conducting surfaces to which external connection may be made by means of contact springs; they may be plated with highly conducting metal such as silver. After assembly of the magnet system in casing 23, and the latter in case 22, a membrane 26 preferably of oiled silk or similar material is added. This is held in position by a metal plate 27 having a central aperture for egress of sound. The case 22 is then formed over the washer 27 by such means as spinning or pressing, completing the assembly.

The air chamber between the diaphragm 13, magnet 12 and casing 23, and the silk covered hole in casing 23 and terminal 21, form the elements of an acoustic network which is designed to give improvement of the frequency characteristics of the receiver as disclosed in British Patent No. 481,351, corresponding to U. S. Patent No. 2,220,942.

Similarly, the air chamber between the diaphragm 13, magnet 11, and plate 27, together with the hole or holes in plate 27, and the hole or holes in the earcap associated with the receiver, form elements of another acoustic network which is designed to give a resonance within the frequency band 2500-3300 as disclosed in British Patent No. 481,740. The filling or sealing compound used to hold the coils 16 and 17 in position may be moulded to have a conical form as described in the latter patent. To prevent undue air damping the inner pole rings of magnets 11 and 12 may have one or more radial grooves cast or cut in the pole faces.

Figs. 3 and 4 show another form of the invention, corresponding elements being similarly numbered wherever practicable. Here each of the magnets 11 and 12 is U-shaped and the ends of the U have opposite polarity. The magnets are moulded into two moulded casings 31 and 32 so that the ground polar faces of the magnets lie in the plane of circular seats on the mouldings. The casings 31 and 32 and magnets 11 and 12 are assembled face to face with the magnetic diaphragm 13 clamped between the casings, so that unlike poles of the two magnets are in juxtaposition to one another on opposite sides of the diaphragm. The spacing washers 14 and 15, which preferably are of thin non-magnetic material and may be either metallic or non-metallic, are placed between each side of the diaphragm and the seats on the mouldings to space the magnets from the diaphragm by an amount equal to the washer thickness. Four windings 33, 34, 35 and 36, are assembled round the limbs of the magnets and sealed in by suitable compound to the recesses provided in the moulded casings 31 and 32. The four windings are connected in series and the insulated leads 19 and 20 are connected respectively to terminal 21 and case 22; grooves and recesses are provided in the mouldings for passage of the leads. The connection and sense of the four windings is such that at any instant when current is flowing in them the magnetic fluxes which they produce in the diaphragm traverse the diaphragm in a direction parallel with its plane, passing from one pole of a magnet to the opposite pole in the same sense so as to be additive. It will be clear that according to the direction of the current and hence of the magnetic flux produced, the diaphragm will be deflected towards one or other of the two magnets 11 or 12.

Figs. 5 and 6 show a third form of the invention. Two channel-section magnets 11 and 12 which preferably extend lengthwise to nearly the full width of the diaphragm 13, are magnetised with opposite polarity at each side of the channel. The magnets are moulded into two moulded casings 31 and 32 and the diaphragm is spaced by washers 14 and 15 in the manner already described for the designs of Figs. 1 to 4. The central part of diaphragm 13 which faces the central area of magnets 11 and 12, is made of non-magnetic material 51 attached by suitable adhesive to the diaphragm. This detail extends the full length of magnets 11 and 12 as seen in Fig. 6. A

single energising coil 52 is used, and the ends are connected to terminal 21 and case 22 as before. The coil is assembled on a core 53 of magnetic material which is fixed by screws 54 to pole pieces of magnetic material 55 and 56. The latter are moulded into the moulding 32 and project through so that their end faces lie close to the diaphragm surface.

A third moulding 57 encloses the coil and is recessed on its outside for terminal 21.

The shallow chamber formed between the diaphragm and moulding 32, the hole in magnet 12 covered by a silk disc 58, and the air chamber enclosed between mouldings 32 and 57, together form an acoustic network which is designed in accordance with the principles disclosed in British Patent No. 481,351 to obtain a uniform response characteristic throughout a wide frequency range.

In any of the above described designs, if desired, the case 22, terminal 21 and plate 27 may be of high permeability magnetic material such as an alloy comprising 78% nickel, 22% iron, or 45% nickel and 55% iron, so that magnetic screening of stray magnetism from the receiver magnets is thereby afforded to other apparatus with which the device is used. This is particularly necessary, for instance, where receivers and transmitters are used in aircraft near to a magnetic compass.

Any of the designs described may be arranged so as to have the driving force applied at the node of the first nodal circle of vibration of the diaphragm. In the design of Figs. 1 and 2, this would correspond to placing the mean circle of the inner pole ring of the magnet at 37.9% of the clamping diameter. Designs Figs. 3 to 6 would have the poles so placed that they lie on the nodal circle and are approximately bisected by

40 it.

Fig. 7 is added as an alternative to the design shown in Figs. 1 and 2. In Fig. 7 there are two annular magnets 11 and 12, together with two yokes 11 and 12, of magnetically soft material, having projecting central portions, the magnetic circuit as before completing its path radially through the armature 13.

What is claimed is:

1. An electro-acoustic reproducer including a magnetic diaphragm, channel shaped magnets positioned on each side and near the central portion thereof, having unlike poles opposite one another, and a speech coil system including an open ended elongated coil having a core and two pole pieces both positioned on one side of said diaphragm, and near the periphery thereof.

2. An electro-acoustic transducer of the type comprising a permanent magnet system, a diaphragm of magnetic material and a speech coil system, in which said diaphragm of magnetic material is so arranged in relation to said magnet system that it is traversed by the steady magnetic flux due thereto and is so arranged in relation to said speech coil system that it is traversed by the alternating magnetic flux due thereto, and in which said speech coil system is spaced from said permanent magnet system and diaphragm and is formed in an elongated shape having a core with pole pieces at opposite ends thereof, said pole pieces being positioned adjacent said diaphragm and in such a manner that the magnetic flux due to said speech coil system traverses said diaphragm in the plane thereof, the relative positions of said permanent magnet system and said pole pieces with reference to

said diaphragm being such that said permanent magnet system is positioned nearer the center of said diaphragm while said pole pieces are positioned nearer the edge of said diaphragm.

3. An electro-acoustic transducer of the type comprising a permanent magnet system, a diaphragm of magnetic material and a speech coil system, in which said diaphragm of magnetic material is so arranged in relation to said magnet system that it is traversed by the steady 10 magnetic flux due thereto, and is so arranged in relation to said speech coil system that it is traversed by the alternating magnetic flux due thereto, said magnet system comprising two similar channel-section magnets, with their poles 15

at each side of the channel, arranged with their opposite poles in juxtaposition on opposite sides of said diaphragm, said diaphragm having two magnetic parts separated by a diametral non-magnetic part lying within the channels, and said speech coil system being spaced from said magnet system and diaphragm and formed in an elongated shape having a core with separate pole pieces at opposite ends thereof, each pole piece being positioned adjacent one of said magnetic parts of said diaphragm, whereby the magnetic flux due to said speech coil system traverses said diaphragm in the plane thereof.

JAMES SAMUEL PATERSON ROBERTON.
